UNITED STATES PATENT OFFICE

BENJAMIN L. FRY, OF ST. LOUIS, MISSOURI

COIN DISPLAY MEANS FOR VENDING MACHINES

Application filed August 18, 1930. Serial No. 475,041.

The present invention has for its object the provision of very simple and compact means whereby the insertion of a slug or spurious device in a coin-controlled machine 5 may be detected, the spurious device being exposed to view so that there can be no dispute as to its presence. The invention is illustrated in the accompanying drawings and will be hereinafter fully set forth.

10 In the accompanying drawings:

Figure 1 is an elevation of a portion of the cabinet of a coin-controlled vending machine having my invention applied thereto,

15 Fig. 2 is a similar view with the face plate removed, and

Fig. 3 is a horizontal section on the line 3—3 of Fig. 1.

20 A portion of the cabinet of a vending machine is indicated at 1 and a portion of the coin chute is indicated at 2. The devices

25 constituting the present invention are disposed below the operating mechanism of the vending machine and it is to be understood that the coin chute is equipped with mechanism whereby the proper coins and all slugs or other spurious devices will be separated as they move past the operating mechanism, the coins being caused to follow a path which will result in operation of the

30 machine and effect a sale while the spurious devices will be diverted to a side path but eventually returned to the same exit as the coins. In carrying out the present invention, an opening is formed in the wall or door

35 of the cabinet and a plate of glass or other transparent material 20 is inserted in said opening. On the outer side of the cabinet or the door, a face plate 3 is secured over the opening and this face plate has a slot or sight

40 opening 4 therein which is of arcuate formation whereby it will expose a portion of a star wheel 5. Said star wheel 5 is mounted on the back of the door or casing wall within a housing 6 which may be a single casting or

45 shallow plate having a recess 7 formed therein to accommodate the star wheel and the deposited slugs and coins. The casing or plate 6 is provided with an arcuate rib 8 defining one side of the recess 7 disposed concentric

50 with the star wheel 5 and at such a distance

from said wheel as to accommodate the deposited coins and slugs and guide them in their passage to the coin box, it being noted that the teeth or points 9 of the star wheel are spaced apart a distance approximating 55 the diameters of the coins intended to operate the machine and said coins and slugs, indicated at 10, being caused to follow a path corresponding to the arcuate portion of the slot 4, as will be understood upon reference 60 to Fig. 1. It is, therefore, evident that the coins and other devices will be exposed to view during their passage to the coin box and the owner of the machine will be furnished with positive evidence that a slug or 65 spurious device has been inserted. Any inquiry of a would-be customer as to why his deposit did not effect a sale will be effectually answered by merely pointing to the exposed 70 slug.

It is, of course, desirable that the passage of the devices to the coin box be retarded so that there will always be an opportunity to observe what devices are passing to the coin box and in the embodiment of the invention 75 illustrated there will be four coins or other devices exposed at all times or at least the first coin deposited will not be discharged until at least four deposits have been made. To effect the desired retardation and permit 80 the device to operate with a step by step motion, a detent 11 is pivoted within the casing 6 above the star wheel and at one side of the mouth or entrance 12. This detent has a short 85 arm 13 projecting into the path of the entering coin, as shown by the full lines in Fig. 2, and a long arm 14 which extends past the star wheel and has its terminal 15 bent inwardly so that it is adapted to enter the successive pockets of the star wheel and abut the 90 teeth or points of the same so as to arrest the movement thereof. When a coin passes through the mouth 12 of the casing 6, however, it will impinge upon the shorter arm 13 and rock the same so that the longer arm 14 95 will be swung out of engagement with the star wheel, as shown by the dotted lines in Fig. 2. This rocking of the detent will also permit the coin to clear the same and enter 100 the pocket defined by the points or teeth 9

which happen to be below the coin and the weight of the coin will effect the rotation of the wheel, it being noted that the mouth 12 is disposed at one side of the vertical plane of the axis of the wheel so that the weight of the coin will be imposed eccentrically upon the wheel. The casing or plate 6 is formed with an opening 16 therethrough so that the owner of the machine, when closing a day's business, may insert a finger and engage the detent 14 to release the same from the star wheel and permit all the coins to pass to the coin box.

The present device is exceedingly simple and compact and may be readily applied to any vending machine at a very low expense.

Having thus described the invention, I claim:

A device of the character described comprising a casing adapted to be secured against a wall of a cabinet and provided with a shallow chamber having an open side closed by the cabinet wall and a coin inlet throat leading from the top of the chamber and a lower outlet opening, a star wheel housed in said chamber and pivoted to said plate with its pivot located to one side of the axis of the inlet throat and its arms moving across the inlet and outlet as the wheel rotates, and a detent pivoted to said plate and shielded by the plate, said detent being located above the star wheel at one side of the inlet throat and having arms extending downwardly in diverging relation to each other, one arm being longer than the other and having its lower end bent inwardly to engage along a top edge of an arm of the star wheel and prevent rotation thereof, an opening being formed in the casing whereby access may be had to the long arm of the detent to move the same out of engagement with the star wheel and permit free rotation of the star wheel, the other arm being short and normally extending into the lower end of the throat for engagement by a coin dropped into the throat whereby the weight of the coin may move the detent and swing its long arm out of engagement with the star wheel to permit the wheel to rotate.

In testimony whereof I affix my signature.

BENJAMIN L. FRY. [L. S.]
